COMBINED NAPKIN HOLDER AND CRUET STAND

Arthur Koretz, 10-01 162nd St., Whitestone, N.Y.
11357, and Harry Lowenstein, 3475 Greystone Ave.,
Bronx, N.Y. 10463

Filed Feb. 21, 1974, Ser. No. 444,431

Term of patent 7 years

Int. Cl. D7—06

U.S. Cl. D7—72

FIG. 1 is a top plan view of a combined napkin holder and cruet stand embodying our new design;

FIG. 2 is a bottom plan view thereof;

FIG. 3 is a side elevational view thereof; and

FIG. 4 is an end elevational view thereof.

We claim:

The ornamental design for a combined napkin holder and cruet stand, as shown.
